UNITED STATES PATENT OFFICE.

TEMPE WHITEHEAD HOLT, OF ROCKY MOUNT, NORTH CAROLINA.

DESIGN FOR A BADGE.

•60,344.

Specification for Design.

Patented Feb. 7, 1922.

Application filed August 29, 1921. Serial No. 496,717. Term of patent 14 years.

To all whom it may concern:

Be it known that I, TEMPE WHITEHEAD HOLT, a citizen of the United States, and a resident of Rocky Mount, in the county of Nash and State of North Carolina, have invented a new, original, and ornamental Design for Badges, of which the following is a specification, reference being had to the accompanying drawing, forming part thereof.

The figure is a plan view of a badge, showing my new design.

I claim:

The ornamental design for a badge, as shown.

TEMPE WHITEHEAD HOLT.
